HERBERT WATKINS JOHNSON, OF LONDON, ENGLAND.

HAIR-WAVING DEVICE.

Application filed May 3, 1926, Serial No. 106,259, and in Great Britain August 27, 1925.

This invention relates to hair waving devices and has for its object to provide an improved device applicable for setting the hair in a wave during the process known as 5 water waving.

According to my invention the hair waving device comprises a pair of combs movably connected in such a manner that when folded together in the hair the two sets of 10 comb teeth co-operate in forming a ridge or wave of hair.

In the accompanying drawings, illustrating a preferred embodiment of the invention:—

15 Figure 1 is a front view of the device with the combs in their closed position;

Fig. 2 is a top view thereof; and,

20 Fig. 3 is a front view showing the combs in open position.

25 In carrying the invention into effect according to the preferred form the improved hair waving device comprises a pair of combs 1—2 curved in the direction of their length to approximate to the curvature of the head and connected at one end by a pivot or hinge 3 allowing partial rotary movement of either comb relatively to the other. The combs are disposed and connected in such a manner that when closed 30 the teeth 4 of one comb rest in the spaces between the teeth 5 of the other comb, both sets of teeth lying approximately in the same plane. To maintain the combs in this position against unintentional displacement 35 when the device is in use the end of each comb remote from the pivot is formed with a hook and the two hooks 6—7 thus formed being oppositely directed enable the combs to be secured together when in their closed 40 position by causing the hooks to engage.

The mode of using the device above described is as follows:—

45 The combs are opened to the extent of approximately a right angle and one of them is inserted in the hair which has been

previously damped, this comb being held in position whilst the second comb is inserted in the hair and moved towards the first comb. When the two combs interengage in their closed position a wave or ridge of hair 50 is formed above and between them and the combs are locked together by engaging the hooks at their free ends. The combs are left in this position until the hair is dry 55 when they are removed leaving a wave in the hair at the position which they have occupied.

The device above described may be made in any material suitable for the manufacture of combs and having the requisite degree of flexibility such as celluloid, casein products, gallolith or metal.

It is to be understood that the invention is not limited to the exact details of construction above described as modifications 65 may be made therein, for example, by employing securing means other than the pair of hooks described.

What I claim is:

1. A hair waving device comprising a 70 pair of combs pivotally connected together at one end and formed with interengaging hooks at their opposite ends, each of said combs being curved in the direction of length and having interfitting teeth.

2. A hair waving device comprising a 75 pair of combs pivotally connected together at one end and provided at their opposite ends with means for fastening the combs in their closed position, each of said combs being curved in the direction of length and having interfitting teeth.

3. A hair waving device comprising a 80 pair of combs pivotally connected together at one end for relative swinging movement, 85 each of said combs being curved in the direction of length and having interfitting teeth lying substantially in the same plane.

HERBERT WATKINS JOHNSON.
